(57) **CLAIM**

The ornamental design for a tool tray, as shown and described.

DESCRIPTION

FIG. 1 is a top front right perspective view of a tool tray according to our design;

FIG. 2 is a top rear left perspective view thereof;

FIG. 3 is a top view thereof;

FIG. 4 is a front view thereof;

FIG. 5 is a back view thereof; and,

FIG. 6 is a right side view thereof, a left side view being a mirror image of the view shown.

The bottom of the tool tray is unadorned and forms no portion of the claimed design. The broken line shown at the bottom margin of the tool tray in FIG. 6 illustrates environment that forms no part of the claimed design.

1 Claim, 5 Drawing Sheets
